Primary Examiner—Celia A. Murphy*(74) Attorney, Agent, or Firm*—Michael E. Zall(57) **CLAIM**

I claim the ornamental design for a pair of shoe outsoles, as shown and described.

DESCRIPTION

FIG. 1 is a perspective view of the left odd of a pair of shoe outsoles showing my new design; the right sole being a mirror image, and being removed for convenience of illustration. And the broken lines showing a shoe upper illustrates the portion of the design that forms no part of the claim;

FIG. 2 is a left side elevational view thereof;

FIG. 3 is a right side elevational view thereof;

FIG. 4 is a bottom plan view thereof;

FIG. 5 is a rear elevational view thereof; and,

FIG. 6 is a front elevational view thereof.
